[57] CLAIM

The ornamental design for a prosthetic bridge part, as shown and described.

DESCRIPTION

FIG. 1 is a top perspective view of a prosthetic bridge part showing a first embodiment of our new design;

FIG. 2 is a bottom perspective view thereof;

FIG. 3 is a top plan view thereof;

FIG. 4 is a side view thereof, the opposite side view being a mirror image;

FIG. 5 is a bottom plan view thereof;

FIG. 6 is an end view thereof, the opposite end view being identical;

FIG. 7 is a top perspective view of a prosthetic bridge part showing a second embodiment of our new design;

FIG. 8 is a bottom perspective view thereof; and

FIG. 9 is a top plan view thereof;

FIG. 10 is a side view thereof, the opposite side view being a mirror image;

FIG. 11 is a bottom plan view thereof;

FIG. 12 is an end view thereof; and,

FIG. 13 is the opposite end view thereof.
